UNITED STATES PATENT OFFICE

96,744

DESIGN FOR A HAIR DRYING APPARATUS

Samuel Grant, Chicago, Ill., assignor to General Corporation of America, Chicago, Ill., a corporation of Illinois

Application July 11, 1935, Serial No. 57,590

Term of patent 7 years

To all whom it may concern:

Be it known that I, Samuel Grant, a citizen of the United States, residing at Chicago, in the county of Cook and State of Illinois, have invented a new, original, and ornamental Design for a Hair-Drying Apparatus, of which the following is a specification, reference being had to the accompanying drawing, forming a part thereof.

The figure is a perspective view of the hair-drying apparatus, showing my new design. The other side of the device, not shown in the drawing, is substantially like the side shown.

I claim:

The ornamental design for a hair-drying apparatus substantially as shown and described.

SAMUEL GRANT.
